UNITED STATES PATENT OFFICE.

CHARLES SANGSTER AND ALVA R. ORMSBY, OF MANSFIELD, ASSIGNORS TO
SAID ORMSBY, AND NELLIE M. BRADMAN, OF BOSTON, MASSACHUSETTS.

COMBINED MOP AND WRINGER.

SPECIFICATION forming part of Letters Patent No. 413,095, dated October 15, 1889.

Application filed July 9, 1889. Serial No. 316,979. (No model.)

To all whom it may concern:

Be it known that we, CHARLES SANGSTER and ALVA R. ORMSBY, both of Mansfield, in the county of Bristol, State of Massachusetts, have invented certain new and useful Improvements in a Combined Mop and Wringer, of which the following is a description sufficiently full, clear, and exact to enable any person skilled in the art or science to which 5 said invention appertains to make and use the same, reference being had to the accompanying drawings, forming part of this specification, in which—

Figure 1 is an elevation of our improved 15 mop, a portion of the rod being broken away and the cloth in position for use; Fig. 2, a like view showing the method of wringing; Fig. 3, a sectional view of a portion of the handle and cap; Fig. 4, top plan views of the 20 handle, the cap being removed; Fig. 5, a bottom plan view of the mop, the cloth being detached; and Fig. 6, a sectional view illustrating a modification of the improvement.

Like letters of reference indicate corresponding parts in the different figures of the 25 drawings.

Our invention relates to a combined mop and wringer; and it consists in certain novel features hereinafter fully set forth and 30 claimed, the object being to produce a simpler, cheaper, and more effective device of this character than is now in ordinary use.

The nature and operation of the improvement will be readily understood by all 35 conversant with such matters from the following explanation.

In the drawings, A represents the mop-handle, and B the cloth. The handle A is circular in cross-section, and is provided with a 40 longitudinal slot or groove b. A sleeve or ferrule d is secured to the lower end of said handle, and to said ferrule a laterally-projecting cloth loop or holder f is secured at one side the groove b. A rod g is fitted to 45 slide longitudinally in the groove b, and a cloth loop or holder h is secured to the lower end of said rod, said holders f h registering when the rod is withdrawn, as in Figs. 1 and 5.

A cap or handle proper D is fitted to slide 50 on the upper end of the handle A, the corresponding end of the rod g being bent at i and secured in the head j of said cap.

The cloth B is cylindrical and passes through the holders f h. When the handle D is withdrawn into the position shown in Fig. 1, the holders f h register and the cloth is looped in position for use in scrubbing. By forcing the cap D downward into the position shown in Figs. 2 and 3 the rod g is projected through the groove b, causing the holder h to be forced downward and distend the cloth B. By rotating the cap D on the handle A the holder h is revolved, (see dotted lines in Fig. 5,) twisting the cloth around the rod g, and thereby wringing it in a manner readily understood without a more explicit description.

The cap D may be dispensed with, if desired, and the upper end of the rod g looped at m to form a handle, the rod being retained 70 in the slot by rivets p, passing through the walls thereof, as shown in Fig. 6.

Owing to the construction of the handle A with the groove b, open at the side of the handle throughout the length thereof, the 75 rod g can be quickly inserted in the handle whereby the parts are rapidly assembled in the manufacture of the mop. Moreover, the groove can be cut more economically than by a boring operation.

Having thus explained our invention, what 80 we claim is—

1. The combination of a mop-handle provided with a longitudinal groove, a cloth loop attached to said handle, a rod disposed 85 in the groove in said handle, a cloth loop attached to said rod, and a sliding cap on said handle, the upper end of said rod being secured to said cap, substantially as described.

2. In a mop, the combination of a handle 90 grooved longitudinally, a ferrule on one end thereof, a cloth-holder on said ferrule, a cap sliding on the opposite end of said handle, a rod sliding in said groove and secured to said cap, and a holder on said rod, substantially as described.

CHARLES SANGSTER.
ALVA R. ORMSBY.
